UNITED STATES PATENT OFFICE.

ERVIN H. SMITH, OF NEW LONDON, WISCONSIN.

PRICE-TAG OR CARD HOLDER.

1,390,172.

Specification of Letters Patent. Patented Sept. 6, 1921.

Application filed October 5, 1920. Serial No. 414,799.

To all whom it may concern:

Be it known that I, ERVIN H. SMITH, a citizen of the United States, residing at New London, in the county of Waupaca and State 5 of Wisconsin, having invented certain new and useful Improvements in a Price-Tag or Card Holder, of which the following is a specification.

This invention relates to price tag or card 10 holders.

The object of the invention is to provide a simply constructed device of this character especially designed for use on covers of containers, shelves and the like to exhibit 15 a card containing any desired indicia.

Another object is to provide a one-piece sheet like structure for securely holding a card to be exhibited against accidental displacement and at the same time protecting 20 the card held against injury incident to handling.

With these and other objects in view, the invention consists in certain novel features of construction as hereinafter shown and 25 described and then specifically pointed out in the claims, and in the drawings illustrative of the preferred embodiment of the invention.

In the accompanying drawings:

30 Figure 1 represents a perspective view of a card holder constituting this invention shown applied.

Fig. 2 is a front elevation thereof detached.

35 Fig. 3 is an edge view thereof, and,

Fig. 4 is a central vertical section taken on the line 4—4 of Fig. 2.

The holder constituting this invention is shown applied to the cover *c* of a container 40 *C* here shown in the form of a crock although obviously it may be of any other form. A handle *H* is shown connected with the cover *c* by oppositely extending arms *A* having hooked terminals to clip around the edge of 45 the cover as is shown clearly in Figs. 1, 3 and 4.

The holder constituting this invention comprises a sheet or plate 1 composed of any suitable material such as sheet tin, 50 aluminum or any other suitable material. This sheet 1 has parallel rectilinear side edges provided with inturned card retaining

flanges 2 which are spaced from the plate a sufficient distance to permit a card or tag *T* to be slipped between the flanges and the 55 plate forming guides for the tag as well as means to hold it engaged with the plate.

The upper end of the plate 1 is here shown polygonal in configuration, although obviously it may be of any other desired form 60 and the edges thereof are folded rearwardly against the rear face of the plate to form reinforcing means for the upper edge of the plate.

The lower edge of the plate 1 has a card 65 retaining slip or tongue 4 struck out therefrom by slitting said edge at spaced intervals and bending the tongue 4 so formed inwardly with an outward bulge 5 intermediate its ends to adapt the free end 70 thereof to snugly engage the front face of the plate to have a clamping engagement with the tag *T* placed between said tongue and said plate as is shown clearly in Fig. 1. The free edge of this tongue 4 is preferably 75 folded inwardly as shown at 6 to facilitate the insertion of the tag *T* and provide sufficient rigidity for this portion of the tongue.

The slitting of the lower edge of the plate 1 to form tongue 4 provides arms 7 at opposite ends of the tongue and these arms have their terminals bent to form support engaging elements 8. These bent terminals have parallel upper and lower jaws 9 and 10 which are designed to receive between them 80 the support on which the holder is to be mounted and which is here shown in the form of the cover *c* (see Figs. 3 and 4). Obviously these support engaging elements may be hooked over a shelf or any other 85 suitable support and when so engaged will securely retain the holder in upright position as shown in the drawings.

This one-piece sheet metal holder may be very cheaply constructed and will operate 90 not only to hold a tag engaged with a support but will form a backing therefor and prevent the tag from being warped or torn which often occurs incident to handling. It is of course understood that any desired 100 indicia may be printed on the tag, it being especially useful to support price tags employed in grocery stores and other places.

The preferred embodiment of the inven-

tion is disclosed in the drawings and set forth in the specification, but it will be understood that any modifications within the scope of the claims may be made in the construction without departing from the principle of the invention or sacrificing any of its advantages.

What is claimed is:

1. A device of the class described comprising a sheet metal plate provided with card retaining flanges, the lower edge of said plate having an upturned inwardly extending spring clip for clampingly engaging a card to be held, and support en-

gaging means carried by said plate comprising laterally rearward, downward and forwardly extending flanges.

2. A device of the class described comprising a sheet metal plate having card retaining means at the side edges thereof, and an inwardly extended tongue struck out and forming a spring clip at its lower edge for clampingly engaging a card to be held, said lower edge being provided with support engaging clamping elements.

In testimony whereof, I affix my signature hereto.

ERVIN H. SMITH.
